UNITED STATES PATENT OFFICE.

FRANCIS A. WALSH, OF MILWAUKEE, WISCONSIN.

DIE FOLDING AND SEAMING MACHINE.

SPECIFICATION forming part of Letters Patent No. 445,738, dated February 3, 1891.

Application filed April 23, 1889. Serial No. 308,317. (No model.)

To all whom it may concern:

Be it known that I, FRANCIS A. WALSH, of Milwaukee, in the county of Milwaukee, and in the State of Wisconsin, have invented certain new and useful Improvements in Die Folding and Seaming Machines; and I do hereby declare that the following is a full, clear, and exact description thereof.

My invention relates to die folding and seaming machines, being somewhat analogous to what is set forth in my applications, Serial Nos. 332,267 and 332,268, filed December 2, 1889, as well as in my application Serial No. 366,478, filed September 29, 1890; and it consists in certain peculiarities of construction and combination of parts to be hereinafter described with reference to the accompanying drawings, and subsequently claimed.

In the drawings, Figure 1 represents a front elevation of my machine, partly in section; Fig. 2, a side elevation of the same; Fig. 3, an enlarged detail front elevation, partly in section, of certain of the parts shown in Fig. 1; Fig. 4, an enlarged detail side elevation, partly in section, of certain of the parts shown in Fig. 2; Fig. 5, a section on line 5 5, Fig. 2; Fig. 6, a section on line 6 6, Fig. 1; Fig. 7, a detail view of a clutch mechanism that forms part of the machine, and Fig. 8 is a detail view illustrating the folds made by said machine.

Referring by letter to the drawings, A represents the standards, and B the base, of my machine, this base being provided with vertical ribs *a* and lateral arms *b*, the latter and face-plates *c* bolted thereto, serving as bearings for a shaft *C*, that has a crank *C'* connected to a slide *D* by means of an adjustable hanger *E*. The slide *D* works in guides *F*, adjustably connected to the base *B* adjacent to the vertical ribs *a*, and thus said slide may be accurately centered. On its under side the slide *D* is provided with a slot *d*, that extends from front to rear, and recesses on each side of this slot serve to receive dies *f* *h*, these dies being held in place by bolts *g* or other suitable means. A portion of the dies extend into the slot *d* and support the shouldered and recessed shank *i* of a plunger *G*, the recesses in said shank serving as seats for the spiral springs *j*, that bear against the slide *D*.

As shown, the die *f* has a beveled point that conforms to a beveled groove *k* in a shoulder *m* of the plunger *G*, and the die *h* has a beveled groove *g'*, to receive a beveled point *o* on another shoulder *m'* of said plunger, the groove *k* and point *o* being the lower dies of the machine. By beveling the dies the faces of each form an acute angle, and the vertical faces of all said dies will be normally at right angles to an opposing sheet of metal, as shown in Fig. 5. Just above the shoulders *m m'* I provide the plunger *G* with gage-plates *k'*, the latter being more or less thick in proportion to the width of the folds it is desirable to make with the dies.

Carried on the slide *D* is a reservoir *H*, and a duct *H'* leads from this reservoir down through the plunger *G* into a groove *p* in the shoulder *m'* thereof, and serves to conduct flux, cement, or solder from said reservoir to the fold made by the dies *h o*. That portion of the duct *H'* that enters the reservoir *H* is provided with a slot and enters a tube *H''*, having a corresponding slot, while within this tube is a vertically-adjustable stem *H³*, reduced at its lower end to engage said duct and cut off more or less of the slot therein when the slide *D* makes its downward stroke, whereby the flow of the sealing material is regulated. That portion of the duct *H'* above the plunger *G* fits loosely in the slide *D*, so as not to interfere with the vertical movement of said plunger and slide.

As best illustrated in Fig. 5, I prefer to make the reservoir *H* with double walls and connect the space between these walls with a pipe for steam or other heating-fluid, whereby the material in said reservoir may be melted and kept in a liquid state.

Held in the base *B* by means of a set-screw is the shank of a horn *T*, the latter being arranged under and parallel to the plunger, and this horn is provided with gage-pins *t*, controlled by spiral springs *t'*, as best illustrated in Fig. 4.

The crank-shaft *C* carries a drive-pulley *C²*, the latter being normally loose, and on its under side said shaft is grooved to receive a sliding key *c'*, for engagement with a recess *c²* in the hub of said pulley, this engagement being automatically effected by means of a spring *e*, arranged in a transverse slot in the

crank-shaft to bear against the outer end of said key.

A transverse groove of suitable contour is made in the key c' to receive the wedge-shaped end of a lever q , the other end of this lever being pivoted to a stud on the machine, as best illustrated in Figs. 2 and 7. The wedge-shaped end of the lever q is curved so as to correspond with the contour of the crank-shaft C , and is held up against the latter by a rod S , connected to a treadle R , this treadle being controlled by a spiral spring R' , as illustrated in Fig. 1.

While the machine above described is more particularly designed for folding and seaming the edges of sheet metal in the process of making vessels, it is equally well adapted to the folding and seaming of metal sheets for roofing and other purposes.

The operation of the machine for the purpose of folding and seaming the edges of sheet metal in the manufacture of vessels is as follows: A sheet of metal bent into an approximate form of the vessel desired is placed so that the edges thereof rest on the shoulders $m m'$ of the plunger G and against the gage-plates k' . The treadle R is now depressed to actuate the rod S and lever q , whereby the wedge-shaped end of this lever is withdrawn from the slot in the key c' , the latter being forced by the spring e into the recesses c^2 in the hub of the drive-pulley C^2 to start the machine. The revolution of the crank-shaft C actuates the slide D , and the latter descending carries the plunger G down against the horn T , where it is stopped, said slide continuing its descent against the springs j to cause the acute-angled dies $f h$ to engage the metal with the corresponding dies $k o$, whereby the right and left folds shown by Fig. 8 are formed in the opposing edges of the metal sheet. When this operation takes place, the body of the metal sheet inclines toward the vertical faces of the dies, and thus the folds are formed parallel to said die-faces and at acute angles to said body of the metal sheet. The continued revolution of the crank-shaft C carries the movable parts back to their normal position, and at about the finish of said revolution the wedge-shaped end of the lever q will enter the transverse groove in the key c' to automatically withdraw the latter from the recess c^2 in the hub of the drive-pulley C^2 , and thereby stop the action of the machine, the treadle R having been released by the operative. Attention is called to the fact that when the folding operation takes place the body of the metal sheet is free to cant toward the bevel sides of the dies $f o$ to thus insure the formation of the hooks shown in Fig. 8. After the operation of folding has been completed the folded edges of the metal sheet are hooked together and placed on the horn T , after which the machine is again started to cause an impact of the plunger against said folded and interlocked edges of said sheet, whereby the operation of seaming is effected.

As shown in several of the figures, I prefer to provide the lower face of the plunger with an anvil having a groove therein to receive the seam formed by the operation just described.

Having thus described my invention, what I claim as new, and desire to secure by Letters Patent, is—

1. The combination of a reciprocative slide, dies carried thereby, a plunger reciprocative in the slide, dies carried by the plunger in opposition to those first named, and a stop for limiting the travel of the plunger, substantially as set forth.

2. The combination of reciprocative dies, a plunger provided with dies opposed to those first named, and a horn opposed to the plunger, substantially as set forth.

3. The combination of a pair of opposing dies, a groove adjacent to one of the dies for the reception of sealing material, and suitable means for engaging and disengaging said dies, substantially as set forth.

4. The combination of a pair of opposing dies, a reservoir for sealing material, a conduit leading from the reservoir to a point adjacent to one of the dies, and suitable means for engaging and disengaging said dies, substantially as set forth.

5. The combination of a pair of opposing dies, a reservoir for sealing material, a conduit leading from the reservoir to a point adjacent to one of the dies, a regulator for controlling the flow of said material, and suitable means for engaging and disengaging said dies, substantially as set forth.

6. The combination of a pair of opposing dies, a reservoir for sealing material, a conduit leading from the reservoir to a point adjacent to one of the dies, suitable means for keeping the sealing material in a melted state, and a reciprocating mechanism for engaging and disengaging said dies, substantially as set forth.

7. The combination of a reciprocative slide provided with a slot and recesses at each side of the slot, dies fitted in the recesses and projected into said slot, a spring-controlled plunger normally supported by the dies and provided with shoulders in the form of dies opposed to those carried by the slide, and a stop for limiting the travel of the plunger, substantially as set forth.

8. The combination of a reciprocative slide provided with a slot and recessed at each side of the slot, dies fitted in the recesses and projected into said slot, a plunger normally supported by the dies and provided with shoulders in the form of dies, opposed to those carried by the slide, a horn arranged in the path of the plunger, and an anvil carried by said plunger in opposition to the horn, substantially as set forth.

9. The combination of a reciprocative slide provided with a slot and recessed on each side of the slot, dies fitted in the recesses and projected into said slot, a plunger normally sup-

ported by the dies and provided with shoulders in the form of dies opposed to those carried by the slide, gage-plates fitted to the plunger, and a stop for limiting the travel of 5 said plunger, substantially as set forth.

10. The combination of reciprocative dies, a plunger provided with dies opposed to those first named, a horn opposed to the plunger, and spring-controlled gage-pins arranged in 10 the horn, substantially as set forth.

11. The combination of reciprocative dies, a plunger provided with dies opposed to those first named, gage-plates fitted to the plunger, a horn opposed to said plunger, and spring- 15 controlled gage-pins arranged in the horn, substantially as set forth.

12. In a machine for folding single edges of metal sheets preparatory to an interlocking and closing down of opposing folds, a die- 20 point having one face thereof normally at right angles to a sheet to be operated upon and the opposite face of said point beveled in a direction acute to the plane of said sheet, a die-groove corresponding in shape to and 25 in register with the die-point, and suitable means for engaging said point and groove against the sheet, the latter being free to incline toward the non-beveled faces of the die- point and groove when the engagement takes 30 place, whereby a fold is formed parallel to

said non-beveled faces of the die-point and groove and at an acute angle to the body of said sheet, substantially as set forth.

13. In a machine for separately folding the meeting edges of metal sheets preparatory to 35 an interlocking and closing down of opposing folds, two die-points arranged in opposite directions to a sheet in position to be operated upon, and two die-grooves in register with said points, one face of each point and groove 40 normally at right angles to the sheet and the opposite face beveled in a direction acute to the plane of said sheet, and suitable means for engaging both points and opposing grooves against the sheet at the same time, whereby 45 right and left folds are simultaneously formed on the same sheet parallel to the non-beveled faces of the points and grooves and at acute angles to the body of said sheet, the latter being free to incline toward said non-beveled 50 faces when the engagement takes place, substantially as set forth.

In testimony that I claim the foregoing I have hereunto set my hand, at Milwaukee, in the county of Milwaukee and State of Wisconsin, in the presence of two witnesses. 55
